UNITED STATES PATENT OFFICE.

LYMAN WHITON, OF TROY, NEW YORK.

STAY FOR SUPPORTING THE SPINE OF THE HUMAN BODY AND KEEPING THE BODY
ERECT, &c.

Specification of Letters Patent No. 3,795, dated October 12, 1844.

To all whom it may concern:

Be it known that I, LYMAN WHITON, of Troy, in the county of Rensselaer and State of New York, have invented a new and Improved Method of Supporting the Spine of the Human Body and Keeping the Body Erect and Chest Open; and I declare the following to be a full and exact description thereof.

10 By reference to the drawing hereunto annexed, by me subscribed, and described "An improvement to keep erect and support the human body," it will be seen, that I take for said purpose a piece of india rubber, 15 shirred cloth, of sufficient length to reach from about the center between the shoulders of the person, on a line with the top of the shoulder blade, down to the bottom of the spine, varying in length to correspond with 20 the length of the back, of the width of about three inches and six inches long in the center part or middle piece marked on the accompanying drawing A and of about double that width at the top and bottom as marked 25 B and C as the top piece and bottom piece—with two braces marked D and E running from the bottom piece, up under the arm about three inches in length and one in breadth, so as to hold down the shoulder 30 strap marked F. The two top and bottom pieces B and C run and are elastic horizontally, while the middle piece marked A runs and is elastic up and down. The whole is supported by two pieces of whale bone 35 marked G and H, running nearly the whole length of the supporter. The middle piece

marked A is elastic up and down on the back; the end pieces marked B and C are elastic horizontally and the lower end C covers the small of the back.

40 The excellence of the thing described consists in its adaptation to the back, erect or stooping; its elasticity in all its parts so as to suffer the body to bend with ease; its great extension downward so as to support 45 the small of the back and the mode of keeping the brace from pressing too close up under the arm.

Supporters of the back are now known 50 consisting of a top piece like the one marked B, in some measure, used with a middle piece somewhat like A but elastic only to a trifling degree and that horizontally, but my supporter fits the whole back and extends much lower than any supporter here- 55 tofore.

The upper or top piece I do not claim, 60 nor the middle or center piece, horizontally elastic, nor the brace marked F, but

I do claim—

65 The connecting of said top piece marked B and said strap marked F, with said horizontally elastic bottom piece C and said middle piece A, elastic up and down the back, and said elastic braces, operating as 70 aforesaid, whether the supporter be made of india rubber cloth or any other material.

LYMAN WHITON.
